UNITED STATES PATENT OFFICE.

JOHN G. SNYDER, OF ALTOONA, PENNSYLVANIA.

RAILROAD-TIE.

No. 800,599.

Specification of Letters Patent.

Patented Sept. 26, 1905.

Application filed February 14, 1905. Serial No. 245,572.

To all whom it may concern:

Be it known that I, JOHN G. SNYDER, a citizen of the United States, residing at Altoona, in the county of Blair and State of Pennsylvania, have invented certain new and useful Improvements in Railroad-Ties, of which the following is a specification.

My invention relates to improvements in railroad-ties, and one object is the provision 10 of a railroad-tie which will be very durable or have a very long life, rendering the tie more desirable and economical, all matters considered, than the ties in general use.

Another object of my invention is the provision 15 of a railroad-tie which will form a perfect support for the rails, allowing for the necessary expansion and contraction and which will provide a perfect cushion and noise-deadener for the rails, thus insuring a railroad-tie combining every requisite to render 20 the tie thoroughly practical and efficient in every particular.

To attain the desired object, my invention 25 consists of a railroad-tie embodying novel features of construction and combination of parts, substantially as disclosed herein.

Figure 1 represents a vertical longitudinal sectional view of one end of my railroad-tie. Fig. 2 represents a plan view with one of the 30 connecting and fastening plates removed; and Fig. 3 represents a plan view of several ends of the ties with a rail in position or, in other words, a plan view of the complete improvement.

35 In the drawings the letter A designates the hollow casing or jacket or shell of my tie, which is preferably made of metal, and particularly of steel, and this casing is formed near each end with the recesses B, which are 40 formed by the vertical walls C, said walls being formed at their upper edges with shoulders D, in which are adapted to fit the securing-plates E, as will more fully appear.

The casing or shell is entirely filled with a 45 substance, such as concrete or other suitable material F, which will form a perfect solid mass which rests upon the ground, and this construction provides the bed or support G, upon which rests the recessed chair H, in the 50 recess or seat or socket J in which are placed

e lower zinc or deadening plate K and the intermediate lead plate K' and the steel or the upper rail-supporting plate L, upon which rests the foot M of the rail, and the connecting-plates or securing-plates E are retained 55 in place upon the chair and the walls of the tie by means of the vertical fastening-bolts N, the under side of the chair having kerfs N' to secure the fastening-bolts from turning, and the plate E is provided with slots O, which 60 permit the sliding of the plate into position upon the foot of the rail.

From the foregoing description, taken in connection with the drawings, it is evident that I provide a railroad-tie which although 65 initially will cost more than the ordinary wood tie will last for so long a time as to make it really cheaper than the ordinary tie; also, that the tie forms a perfect support for the rail and gives a cushion to insure smooth and even 70 riding and deadens all sound, and also that it can be easily transported and assembled and that its use will fill a long-felt want in a perfect manner.

If desired, I may also place a lead plate under the plates that clamp the rail to the ties, and I have found by experience that the best results are obtained by using a one-inch steel plate, a half-inch lead plate, and a half-inch zinc plate; but these proportions may be 80 changed.

I claim—

1. A railroad-tie consisting of a casing or shell having recesses or chambers near each end, a filling or mass of material in said casing forming a support and a bed under each chamber, a chair fitting in each chamber upon the said bed, and rails mounted and supported upon said chairs.

2. A railroad-tie consisting of a casing or shell having recesses or chambers, a filling or mass in said casing forming a bed for said chambers, chairs resting upon said bed and formed with recesses, a deadening-plate, an intermediate plate and a rail-supporting plate 95 arranged in the recess of the chair, rails mounted on the rail-supporting plates and means for securing the rails in position.

3. A railroad-tie consisting of a metal casing or shell and a filling of suitable material, 100

metal chairs resting upon the filling, deadening and supporting plates seated in said chairs and a rail on the supporting-plate.

4. A railroad-tie consisting of the metal casing having the vertical walls forming recesses or chambers, a support or bed filling said casing, a chair resting in said chamber, a rail supported by said chair, and connecting-plates

engaging the foot of the rail and mounted upon the chair and casing.

In testimony whereof I affix my signature in presence of two witnesses.

JOHN G. SNYDER.
